Primary Examiner—Bernard AnsherAssistant Examiner—Lucy Lieberman*Attorney, Agent, or Firm—Michael J. McGreal; Robert C. Sullivan*[57] CLAIM

The ornamental design for a bottle, as shown and described.

DESCRIPTION

FIG. 1 is a front elevational view of a bottle showing our new design;

FIG. 2 is a side elevational view thereof, rotated 90° from FIG. 1;

FIG. 3 is a rear elevational view thereof, rotated 180° from FIG. 1;

FIG. 4 is a side elevational view rotated 270° from FIG. 1;

FIG. 5 is a top plan view thereof;

FIG. 6 is a bottom plan view thereof; and,

FIG. 7 is a perspective view thereof.

The broken line showing of a cap is for illustrative purposes only and forms no part of the claimed design.
